ABSTRACT: An inertia switch having a two-part housing of electrical insulating material, the lower housing part being provided with a conical ramp surface at its bottom to receive a relatively heavy ball which is adapted to move along the ramp surface in the event of a collision by an automobile, for example, to tilt a disc of electrical conductive material into contact with a flat electrical conductive ring. The ring is provided with a lead in the form of a tab extending through a notch in the housing part to the outside to receive suitable wires or leads. In engagement with the disc and extending through the center of the ring is a coil spring also of electrical conductive material, the upper end of which is disposed in a guide which is rigid with the inside of the upper housing part. Fixed within the guide and engaged by the coil spring is a conductive strip which extends to the outside of the housing through a notch in the housing part for the reception of a wire.

The upper housing part has a depending flange which fits frictionally into the lower housing part to hold the housing parts together and also to bear against the conical ramp may be built-up by increasing the wall thickness to serve as a block for reducing the effective scope of the switch.

INERTIA SWITCH

BACKGROUND OF THE INVENTION

A desideratum exists for a simple, efficient, and foolproof inertia switch particularly for automobiles, which is capable of functioning only in major accidents, and not as a result of minor maneuvers. Such switch must be effective in the event of a major collision, for example, to trigger safety devices, such as an air bag, fire extinguisher, or deenergizing devices. Much effort and expense have been expended in this connection, but the results have not been satisfactory. The switches have been too complex, too expensive, or so delicate they will not stand up under normal usage.

Reference is hereby made to U.S. Pat. No. 3,198,899 issued Aug. 3, 1965, which shows a circuit breaker for vehicles including an inertia operated switch. Although the mechanism therein shown and described is highly satisfactory for certain uses, it is too complex and expensive where a simple inertia switch is required.

SUMMARY OF THE INVENTION

A simple switch mechanism is produced which has the unique ability automatically to determine when the desired combination of G forces and time have been attained, such, for example as may develop in an automobile collision. It can maintain an electric circuit for a time duration during an automobile crash, and reset itself instantly when the G force exerted is reduced to a minimum. The ability to reset itself immediately results that an electric circuit will be maintained only for the duration of the existing G forces. Transitory G forces, no matter how great, if they are not maintained longer than the required time for the electrical surge, cannot operate the switch.

The structure involved consists of a two-part housing which has bracket means enabling it to be mounted in a useful position and the housing parts are held together by frictional engagement. In the lower housing part is a conical ramp on which a relatively heavy ball, such as a steel ball, can freely roll. The lower housing part has two vertically spaced ledges of different diameters, the lower ledge having the shorter diameter and receiving a flat electrical conductive disc. The upper ledge receives a flat electrical conductive ring, which has a lead in the form of a tab extending through a notch in the casing to the outside to receive a suitable wire. In the upper housing part is a guided coil spring of electrical conductive material, which is in constant engagement with the upper face of the flat disc at one end. The opposite end of the coil spring engages a conductive strip which extends through a notch in the upper housing part to the outside to receive the suitable lead.

For restricting the action of the ball and reducing the scope of the switch, a portion of the chamber directly above the conical ramp may be enlarged to block movement of the ball in that direction.

BRIEF DESCRIPTION OF THE DRAWINGS

FIG. 1 is an exploded perspective view showing the several parts of the inertia switch.

FIG. 2 is a vertical sectional elevation of the switch in assembled condition, and

FIG. 3 is a transverse sectional view of a lower housing part showing the manner in which a portion of the chamber may be provided with thicker walls for restricting the effective action of the ball with respect to the ramp surface.

DESCRIPTION OF THE PREFERRED EMBODIMENT

The illustrated embodiment of the invention shown in FIGS. 1 and 2 comprises a vertically disposed housing which is of an electrical insulating or nonconducting material, such as molded plastic material. The housing consists of two parts, an upper part 10 and a lower part 11. On the lower part 11 is a

pair of oppositely extending integral bracket arms 12, which are apertured to receive screws for connecting the switch assembly to a suitable support. In the lower housing part 11, which is in the shape of an inverted triangle, there is a

5 which is in the shape of an inverted dome, there is a chamber having a cylindrical sidewall 13 and a conical ramp surface 14 constituting the bottom wall. Disposed within the chamber and normally resting upon the ramp surface 14 is a ball 15 constituting a spherical mass of high-density material, such as steel. At the upper portion of the chamber are two circular ledges 16 and 17 of different diameters, the lower ledge 16 being of less diameter than the upper ledge 17 and receiving a flat circular disc 18 of electrical conductive material. The disc 18 rests loosely on the ledge 16 so that it can be canted or tilted readily into engagement with a flat ring 19 also of electrical conductive material, which rests on the upper ledge 17. The flat ring 19 has a lead in the form of a lateral tab provided with a reduced neck to fit a notch 21 in the upper portion of the housing part 11. The tab extends outside of the housing to receive a suitable wire.

Engaging a central portion of the flat disc 18 is a coil spring 23 of electrical conductive material. Manifestly, the spring passes freely through the opening in the ring 19 and the upper end fits over a short metallic tube 24 which may be electrically conductive and which is rigid with an electrical conductive strip 25. The strip 25 also has a reduced neck to fit a notch 26 formed in a circular flange 22 which depends from the upper housing part 10. The flange 22 snugly and frictionally engages the lower housing part, as shown in FIG. 2, the lower edge of the flange abutting against the rim portion of the ring 19 to hold it properly in position.

The coil spring 23 is retained in position by a tubular guide 27 which is fixed at its upper end to the inner wall of the upper housing part 10. The housing part 10 is dome shaped. The lower edge of the guide 27 terminates slightly above the upper face of the flat disc 18. The guide 27 has a lateral slot 28 through which the conductive strip 25 extends to the outside of the housing for reception of a suitable lead either from a source of electrical energy or a part to be operated.

40 In response to an effective G force, the ball 15 forces the circular disc 18 away from its ledge and into contact with the flat ring 19, thereby to close the switch. When the G force has been reduced to the preset minimum, the ball 15 moves down the ramp assisted by the weight of the disc 18 and the pressure exerted by the coil spring 23. As soon as the ball starts to move back down the ramp 14, contact is broken between the disc 18 and the ring 19, thereby opening the switch. It will be manifest that opening of the switch is not retarded by friction so that there is no chance of the switch sticking in closed position. As 45 above mentioned, the diameter of the disc 18 is considerably less than the outer diameter of the ledge 16 on which it rests, and this militates against sticking or jamming of the disc 18 in the housing. This also affords a wiping action by the disc 18 against the flat ring 19 as the switch is closed and opened, 50 which assures clean contacts with good conductivity.

It should be understood that the switch will not operate even though a severe impact takes place so long as the forward motion of the vehicle does not continue at least to a small degree. It is important that there be at least some slight motion whether it be forward, rearward, or lateral after the impact for this switch to function. If there is some bending action in either the moving vehicle or the object struck causing a resistance slightly greater than that experienced in a severe braking maneuver and existing for a split second of time, the electrical contacts will then be established.

In some instances, the switch may not be required to work through an arc of 360° as shown in FIGS. 1 and 2, and, as shown in FIG. 3, the wall of the chamber above the ramp is enlarged on that side which is to be blocked. A filler piece 29 is applied to the chamber directly above the conical ramp surface thereby preventing action of the ball on the portion having the filler piece. This may constitute a separate piece suitably positioned within the chamber or the housing part may be moulded to provide such shape.

What I claim is

1. An inertia switch comprising a two-part upright housing of electrical insulating material, the lower part having an open-mouthed chamber having as its bottom wall a conical ramp surface, a relatively heavy ball in said chamber for movement along said ramp surface, a pair of vertically spaced ledges adjacent the open mouth of said chamber with the lower ledge of less diameter than the upper ledge, a flat disc of electrical conductive material seated loosely upon said lower ledge, a flat ring of electrical conductive material on said upper ledge, a tab rigid with said ring and extending laterally from the rim thereof, a notch in said lower housing part adjacent said upper ledge to receive said tab and enable the latter to extend outside of said housing, a depending flange on said upper housing part to fit the lower housing part and bear against said ring for holding same in place, a coil spring guide depending from said upper housing part, a coil spring of electrical conductive material associated with said spring guide extending through said ring and bearing against said disk at its

lower end, a conductive strip engaged at one end portion by said coil spring and extending laterally therefrom outside of the housing, and a notch in said upper housing part through which said strip extends.

5 2. An inertia switch as claimed in claim 1, comprising lateral brackets on one of said housing parts enabling mounting thereof.

10 3. An inertia switch as claimed in claim 1, in which said coil spring guide comprises a cylindrical member rigid with the inner wall of said upper housing part provided with a lateral aperture through which said strip extends.

15 4. An inertia switch as claimed in claim 1, comprising blocking means in said chamber for preventing effective movement of the ball throughout the blocked area, said blocking means increasing the thickness of the walls of a part of the chamber.
